(57) **CLAIM**

The ornamental design for a wing mirror, as shown and described.

DESCRIPTION

FIG. 1 is a front elevation view of the first embodiment of the wing mirror, of the present design;

FIG. 2 is a back elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top, back, left perspective view thereof;

FIG. 8 is a top, front, right perspective view thereof;

FIG. 9 is a front elevation view of a second embodiment of the wing mirror;

FIG. 10 is a back elevation view thereof;

FIG. 11 is a right side elevation view thereof;

FIG. 12 is a left side elevation view thereof;

FIG. 13 is top plan view thereof;

FIG. 14 is a bottom plan view thereof;

FIG. 15 is a bottom, back, left perspective view thereof; and,

FIG. 16 is a bottom, front, right perspective view thereof.

Any broken lines in the figures illustrate portions of the wing mirror that form no part of the claimed design.
